UNITED STATES PATENT OFFICE

ALBERT L. TAYLOR, OF JACKSONVILLE, FLORIDA

PROCESS RETORT

Application filed May 29, 1930. Serial No. 457,207.

This invention relates to retort kilns for the treatment of timber, fibrous and analogous material from which moisture is required to be removed and which may be impregnated with a preservative, germicide, or chemical according to the effect to be produced.

The invention has for its primary object the provision of a quick opening and closing door which assures and maintains a tight joint when closed to prevent loss of pressure or waste of chemical or other material employed in treatment of the material to be processed.

The invention contemplates a retort having a door at each end for progressive treatment, if desired, a system of cylinders and coacting pistons for opening and closing the doors, fastening means for drawing the doors closed by a wedging action, clamp means for subjecting the material to a compressive force during the processing or treatment, and pressure controlled actuating means for the fastening and clamp devices, the operating parts being actuated by fluid pressure, steam, compressed air or other medium, controlled by manually operable valves.

While the drawings illustrate a preferred embodiment of the invention, it is to be understood that in adapting the means to meet specific needs and requirements, the design may be varied and changes in the minor details of construction may be resorted to within the scope of the invention as claimed, without departing from the spirit thereof.

For a full understanding of the invention and the merits thereof, reference is to be had to the following description and the drawings hereto attached, in which:

Figure 1 is a side view of a retort embodying the invention, a door opening cylinder and a controlling valve being shown in section, and illustrating one of the doors open by dotted lines.

Figure 2 is a vertical, central, longitudinal sectional view of the retort.

Figure 3 is a longitudinal sectional view of the retort, on the line 3—3 of Figure 4, looking in the direction of the arrows.

Figure 4 is a transverse sectional view on the line 4—4 of Figure 3.

Figure 5 is an enlarged sectional view of a four-way controlling valve.

Figure 6 is a transverse sectional view of a modified form of retort.

Corresponding and like parts are referred to in the following description and designated in the several views of the drawings by like reference characters.

The numeral 1 designates the cylinder or body of the retort which, in the present instance, is provided at each end with a quick opening and closing door 2. A band or ring 3 is secured within each end of the cylinder a short distance from the extremity thereof. The doors 2 are hinged at any convenient and determinate point, and in the preferable arrangement, the hinge 4 is located at the top to admit of the door swinging upwardly into open position, as indicated by the dotted lines in Figure 1 of the drawings. The doors 2 are of a diameter to fit snugly within the ends of the cylinder 1 and are formed with outer flanges 5 to overlap and engage the respective ends of the cylinder. The outer ends of the bands 3 and cylinder 1 are formed with V-grooves 6 to receive ribs of corresponding shape formed upon the flanges 5 and inner faces of the doors 2, thereby assuring a tight joint to prevent loss of pressure or waste of processing material such as a preservative or germicide. The outer portion of the doors 2 is thick and formed with a peripheral groove or channel 7 which is outwardly flared or of wedge form. Arcuate wedges 8 coact with the grooves or channels 7 and function as fastening means to secure the doors when closed. A cylinder 9 is provided for each of the arcuate wedges 8 and is mounted upon the cylinder 1. A piston 10 in each of the cylinders 9 is connected with an arcuate wedge fastening 8 at an intermediate point and movement of the piston operates the fastener 8 to secure or release the door. The cylinders 9 at each end of the retort are connected by means of a pipe 11 which supplies a motive medium thereto or exhausts the same therefrom in the simultaneous operation of the fastenings 8. A feed pipe 12

100

is connected to the pipe 11 and leads from a suitable source of steam, compressed air, or other fluid medium. A four-way valve 13 is located approximately at the juncture of 5 the feed pipe 12 with each of the pipes 11 to control the fluid pressure supply to the cylinders and to exhaust the spent medium therefrom. The valves 13 are connected by means of a rod 14 for simultaneous operation 10 if desired. When the doors 2 are closed, they are drawn tight and made secure by supplying fluid pressure to the cylinders 9 which actuate the pistons 10 to force the wedge fasteners 8 inward, thereby closing and securing 15 the doors by a wedge action. The wedge fasteners 8 are moved inward by admitting the fluid pressure to the outer ends of the cylinders 9. Upon operating the valves 13 to admit the fluid pressure to the inner ends 20 of the cylinders, the pistons 10 are moved outwardly and withdraw the fasteners 8, thereby releasing the doors which may be quickly opened.

For quick opening of the doors 2, a pair of 25 cylinders 16 is associated with each, the cylinders of each pair being disposed at opposite sides of the retort and inclined upwardly and forwardly from their inner lower ends. A pipe 15 connects the cylinders 16 with the feed pipe 12 and a three-way valve 17 is located in the length of the pipe to control the flow of the fluid pressure to the cylinders. A piston 18 in each of the cylinders 16 has a rod connected thereto and extending 30 through the head of the cylinder and terminating in a slotted cross head 19 to receive the pin 20 or like projecting part of the door. When the door is released it may be thrown quickly into open position by admitting fluid pressure into the cylinders 16 to move the pistons upwardly and forwardly therein. The doors may close by gravitational action, when the valve 17 is operated to exhaust the spent medium from the cylinders 45 16.

A pipe 21 connects with one of the doors 2 and constitutes an outlet. A pipe 22 connects with the opposite door 2 and supplies the medium for treatment of the material to 50 be processed or dried. A pipe 23 connects with the pipe 22 and supplies oil, chemical or other medium to be introduced into the retort. The pipe 22 may lead from a compressor or other source for supplying air under pressure, or for receiving steam or other active medium employed in the process. A valve 24 in the length of the pipe 23 admits of controlling the amount of oil, creosote, or other chemical to be added to the air or steam flowing 55 through the pipe 22, whereby the mixture may be sprayed into the retort for treatment of the material contained therein. A certain percentage of the mixture sprayed into the retort passes off through the outlet 21 and is 60 claimed in any determinate way. Any pres-

sure may be maintained within the retort found most advantageous according to the nature and condition of the material to be treated and the character of the process to which the material is subjected. A gauge 25 is applied to the pipe 23 to indicate the pressure resulting from the mixture flowing from the pipe 22 into the retort. A gauge 26 may be applied to the outlet 21 to indicate the velocity of the outflow from the retort. Other gauges 27, 28 and 29 may be applied to the retort to indicate temperature, moisture and pressure.

The bottom of the retort may be supplied with rollers 30, as indicated in Figure 6 of the drawings, to receive the material and facilitate its introduction into or withdrawal from the retort. If preferred, a track 31 may be located in the bottom portion of the retort, as indicated in Figure 2 of the drawings, to receive trucks 32 upon which the material may be placed, thereby facilitating supplying the material to the retort or withdrawing it therefrom.

When treating timber, it has been found advantageous to clamp the same to retain its shape during extraction of moisture or impregnating the same with a preservative or germicide. The numeral 33 designates clamp members which are connected to pistons 34 mounted upon the retort. A pipe 35 connects the cylinders in which the pistons 34 are disposed and supplies a fluid medium thereto for operating the clamp members to subject the material to compressive action during the processing or extraction of moisture.

A retort constructed in accordance with the invention is adapted for general use in the treatment of timber and other fibrous material required to be cured and processed either by removing moisture therefrom or by impregnating the same with a preservative or insecticide. The doors are quick opening and closing and a tight joint is assured and maintained when the doors are closed, the fastening means operating by a wedge action which draws the doors into closed position, thereby assuring a tight joint. The material, such as timber, may be clamped and subjected to compressive force during the removal of moisture therefrom. This is advantageous in preserving the structure and preventing warping, cracking and other objectionable features which detract from the market value of the commodity. It is observed that the fastening means for the doors, the door opening mechanism, and the clamps are adapted to be readily actuated by manipulating a valve to admit fluid pressure into the proper cylinders, the actuating mechanism being rendered inactive by exhausting the fluid medium from the operating cylinder. These several operations may be easily, quickly and conveniently effected by manipulation of the proper controlling valves as will be readily appreciated.

It is observed that a gasket or packing of any kind may be interposed between the V-shaped joints of the doors and the body of the retort to secure and maintain a tight joint. It is further noted that there is an inner joint 5 that between the band 3 and inner face of the door, and an outer joint, that between the flange 5 and extremity of the body 1, and that these two joints assure a tight closure to prevent any possible escape of internal pressure. The V-form of the joints and the provision of suitable packing therebetween assure a tight joint which is essential under certain conditions.

15. What is claimed is:

1. The combination with a retort body and a door therefor, provided with mating grooves or recesses, of wedge-shaped fastening means for securing the door operable in 20 the grooves or recesses of the body and door, a cylinder for each fastening element, and a piston in the cylinder and connected with the wedge-shaped fastening element at an intermediate point, the cylinders being 25 adapted to receive a fluid medium to effect simultaneous operation of the fastening means.

2. The combination with a retort body and a door, of arcuate wedge-shaped fastening 30 means for the door, and a piston and cylinder constituting operating means for sliding said fastening means radially across the joint between the body and the door.

3. The combination with a retort body and a door therefor, each having mating recesses, 35 of wedge-shaped fastening means slidable radially in the recesses across the joint formed between the body and door, and means for effecting simultaneous movement of the 40 fastening means.

4. The combination with a retort body and a door therefor, of wedge-shaped radially movable fastening means engaging the body and door for drawing the door into closed 45 position to assure and maintain a tight joint, and means for simultaneously operating the fastening means.

5. The combination with a retort body and a door therefor, of arcuate radially movable 50 fastening means of wedge cross section carried by the body and movable into wedge-shaped recesses of the door for securing the door, and cooperating cylinders and pistons for operating the fastening means simultaneously.

6. The combination with a retort body and a door therefor, of wedge-shaped curved fastening means disposed in an annular series on the body around the door and movable 60 radially into wedge-shaped recesses in the edge of the door for securing the door, cylinders mounted upon the body, and pistons in the cylinders connected with said fastening means.

65. 7. The combination with a retort body and

a door snugly fitted within the body and having an outer flange overlapping the extremity of the body, there being a V-joint between said flange and the inner face of the door, of wedge-shaped fastening devices 70 carried by the body and movable radially into recesses in the door to maintain said joint tight.

8. The combination with a retort body having an inner projection a short distance 75 from the end of the body provided with a V-groove, of a door fitting within the end of the body and having a V-rib engaging said groove, and wedge-shaped fastening devices carried by the body and movable radially into recesses formed in the door to force said rib into said groove and maintain a tightly sealed joint therebetween.

9. The combination with a retort body having an inner projection a short distance from 80 the end of the body, and having a V-groove formed in the extremity of the body, and having a V-groove formed in the outer face of said projection, of a door fitting within the end of the retort body and having a V-rib 85 to enter the V-groove of the projection, and having an outer flange overlapping the end of the body and provided with a V-rib to enter the V-groove in the extremity of the body, and wedge-shaped fastening devices 90 carried by the body and movable radially into recesses formed in the door between both of said V-grooves adapted to force said ribs into said grooves and maintain tightly sealed joints therebetween.

In testimony whereof I affix my signature.
